CLAIM

The ornamental design of a housing for a beverage dispenser, as shown and described.

DESCRIPTION

FIG. 1 is a top, left, front perspective view of a housing for a beverage dispenser showing our new design;

FIG. 2 is a front elevational view of the housing for a beverage dispenser of FIG. 1;

FIG. 3 is a top plan view of the housing for a beverage dispenser of FIG. 1;

FIG. 4 is a rear elevational view of the housing for a beverage dispenser of FIG. 1;

FIG. 5 is a bottom plan view of the housing for a beverage dispenser of FIG. 1; and,

FIG. 6 is a left side elevational view of the housing for a beverage dispenser of FIG. 1, the right side elevational view being a mirror image thereof.

The broken line showing of a control panel pads and three spouts in FIGS. 1 and 2, and spout in FIG. 6 are for illustrative purposes only and forms no part of the claimed design.
